(57) **CLAIM**

The ornamental design for an exhaust flow control ring for semiconductor deposition apparatus, as shown and described.

DESCRIPTION

FIG. 1 is a perspective view of an exhaust flow control ring for semiconductor deposition apparatus, FIG. 2 is a front elevational view of the exhaust flow control ring for semiconductor deposition apparatus, FIG. 3 is a rear elevational view of the exhaust flow control ring for semiconductor deposition apparatus, FIG. 4 is a left side elevational view of the exhaust flow control ring for semiconductor deposition apparatus, FIG. 5 is a right side elevational view of the exhaust flow control ring for semiconductor deposition apparatus, FIG. 6 is another view of the exhaust flow control ring for semiconductor deposition apparatus, FIG. 7 is another view of the exhaust flow control ring for semiconductor deposition apparatus; and, FIG. 8 is a rear perspective view of the exhaust flow control ring for semiconductor deposition apparatus.
